UNITED STATES PATENT OFFICE.

ALFRED E. WALLER, OF BRONXVILLE, NEW YORK, ASSIGNOR TO WARD LEONARD ELECTRIC COMPANY, A CORPORATION OF NEW YORK.

APPARATUS FOR CONTROLLING ELECTRIC CIRCUITS.

Application filed April 7, 1922. Serial No. 550,293.

To all whom it may concern:

Be it known that I, ALFRED E. WALLER, a citizen of the United States, residing at Bronxville, in the county of Westchester 5 and State of New York, have invented certain new and useful Improvements in Apparatus for Controlling Electric Circuits, of which the following is a specification.

This invention relates to controlling apparatus for the control of a number of different electric circuits such as for changing the electric lighting effects in theatres. This is usually accompanied by dimmer equipment in which one or more banks of 15 rheostats or other controlling means, are varied or adjusted to give the effects desired from time to time.

In the control of the lamps on different circuits, it is sometimes desirable to control 20 all of the lights similarly and simultaneously by a common actuating means; also in some cases to control one or more of the lighting circuits separately and independently of the common means; and it is 25 also desirable at times to control some of the lighting circuits similarly to a certain extent and then a portion of the circuits to a further degree while others are permitted to remain in a desired condition, 30 such as where the lights on several circuits are dimmed simultaneously to a certain extent, while a portion of the lights are dimmed to a further degree and others allowed to remain partly dimmed. The controlling apparatus, where used in motion 35 picture theatres, is preferably operated by the motion picture operator and therefore must be adapted to be conveniently and quickly operated and occupy as small a 40 space as possible.

The main object of my invention is to produce an improved controlling apparatus which will fulfill these requirements. By use of my invention the operator can 45 quickly and conveniently control any desired number of circuits by the operation of a single driving means and also obtain such flexibility of control that any desired number of the circuits can be controlled to the 50 extent desired and automatically released from further adjustment or control at any desired point, either individually or collectively to any extent desired. Other objects and advantages of my invention will be 55 understood from the following description.

and accompanying drawings which illustrate one embodiment thereof.

Fig. 1 is a front elevation; Fig. 2 is a cross section on the line 2—2 of Fig. 1; Fig. 3 is a similar view enlarged of a part 60 of the apparatus; Fig. 4 is a front elevation of the parts shown in Fig. 3, certain parts being broken away and partly in section; Fig. 5 is a view similar to Fig. 4 showing a part of the controlling apparatus in a different position; Fig. 6 is a plan view of one of the parts; Fig. 7 is an end view of another one of the parts; and Fig. 8 is a sectional view showing part of the adjustable tripping means. 70

In this instance a number of rheostats 10 is shown as the controlling means, although in some cases other controlling devices may be used for affecting the lights in the different circuits controlled. The rheostats 75 here shown are in the form of plates having the resistance wires embedded in adhesive insulating material and connected to the rheostat contacts 11. In this case two circular rows of contacts are shown over 80 which travels the contact arm 12 for varying the amount of resistance in the circuit controlled thereby and thereby affecting the lights as desired. A stop 13 limits the travel of the contact arm and in the position shown in Fig. 2, we may assume that the contact arm is in the resistance-all-out 85 position and that the lights have their full brilliancy. The contact arm 12 in this instance has a hub 14 around which is passed 90 a link chain 15, the ends of which are connected to a bow 16 adapted to be moved by a rod 17. Movement of the rod and bow endwise will obviously turn the contact arm about its center and adjust its 95 position as desired.

A bank of these plate rheostats is shown in Fig. 1 supported by a suitable frame in Fig. 1 formed of cross pieces 18 and upright pieces 19. A main drive shaft 20 is journaled in bearings supported upon the upper part of the frame and is operated by the worm wheel 21 driven by a worm 22 on a shaft 23 carrying an operating hand wheel 24. 100

Each rheostat is adapted to be connected with and operated by the drive shaft 20, by means of manually adjustable apparatus, which is more fully shown in Figs. 3 to 8. 105

Loosely mounted on the shaft is a quadrant or sector 25, and this quadrant has a 110

depending lug 25' by which the quadrant is held in a fixed position by being bolted to a bracket 26 which in turn is bolted to one of the cross pieces 18 of the main frame support. The rim of the quadrant is notched or perforated by a series of holes 25''. A thin indicating plate 27 has perforations 27'' corresponding with the perforations in the rim of the quadrant and is secured to the quadrant; and the holes may be marked or suitably numbered to indicate the various positions for convenience in adjustment. A sheet metal element 28 has its inner end loosely embracing the drive shaft 20 and its outer end is bent so that a portion 28' extends over the scale plate 27 and acts as a carrier for a pin 29. The pin 29 passes through the portion 28' of the carrier and the inner end of the pin projects and is adapted to enter the holes 27'' and 25''. The inner end of the carrier 28 which embraces the shaft 20 has an elongated slot 28'' as shown in dotted line in Fig. 3, which permits the carrier 28 and pin 29 to be conveniently drawn outwardly to disengage the end of the pin from a quadrant hole and may then be swung to any desired position opposite another hole in the quadrant and pushed inwardly in its new position. The carrier and pin may thus be quickly moved to and retained in any position desired, a spring washer 30 on the drive shaft interposed between the inner end of the carrier and another element on the shaft serving to yieldably retain the carrier in any position it may be placed.

A collar 31, having a slot 31', is fixed to the drive shaft. A member 32 is pivotally mounted upon the drive shaft 20 by means of a pair of legs 32' which embrace the collar 31. Slidably mounted in the member 32 is a rod 33. A spiral spring 34 surrounds this rod and is seated between the upper portion of the member 32 and a pin and washer on the rod and thus tends to normally force the rod 33 into the slot 31' of the collar 31. When the rod 33 is thus engaged with the collar 31, the member 32 is locked to the drive shaft 20. From the upper portion of the member 32 extends a pair of lugs 32'', to which is connected the upper end of the rod 17. Angular movement of the member 32 will consequently cause movement of the rod 17 and thereby operate the contact arm 12 of the rheostat.

A handle 35 is fixed to the upper end of the rod or plunger 33. A collar 36 is also fixed to the rod 33 near the handle and has a depending projection 36'. The upper end of the member 32 has a cam surface and has two diametrically opposite depressions 37, 37' between which are two diametrically opposite raised portions or projections 38, 38'. The projection 36' is adapted to engage either of the depressions 37, 37' and when

so engaged, the rod 33 is in engagement with the slot 31' in the collar 31, but turning the handle 35 or rod 33 on their axis causes the projection 36' to ride up on the cam surfaces and when on either projecting portion 38, 38', the rod 33 is withdrawn from engagement with the collar 31 and the handle element is then disengaged from the drive shaft 20. A flat fan shaped element 39 is also fixed to the rod 33 and is shown located between the handle and the collar 36 and projects outwardly from the rod 33 so that when the handle is moved angularly in a plane parallel with the plane of the quadrant, the element 39 travels in a path extending over the quadrant and will be engaged by the pin 29 at a point determined by the position of the pin on the quadrant.

Each of the rheostats of the bank is, or may be, provided with the controlling means above described and by means thereof the rheostats may be simultaneously and similarly adjusted or independently affected or controlled as desired. By turning the handle 35 of any rheostat so that the projection 36' is on a raised portion 38 or 38' of the cam, the member 32 is released from the drive shaft 20 and each rheostat can thus be operated independently of the others by moving the handle about the shaft 20. If the handle 35 is turned so that the projection 36' be in the depression 37', the element 39 is turned away from the pin 29, and the element 32 is then adapted to be moved by shaft 20 by reason of the rod 33 engaging the slot in the collar 31. The latter condition also occurs if the handle is turned so that the projection 36' engages the depression 37' and the element 39 extends toward the quadrant, provided the pin 29 is in an extreme position on the quadrant as shown in Figs. 2, 3 and 4. But if it be desired to cause the automatic release of the member 32 from the shaft at any predetermined point of its travel, pin 29 will be pulled away from the quadrant sufficiently to clear the holes therein and the pin and its carrier may then be swung to any position desired upon the quadrant and the pin then pushed into one of the holes in the quadrant, as shown in dotted lines in Figs. 3 and 4.

Now with the rheostat in the resistance-all-out position shown in Fig. 2 and the handle in its upper position, the turning of shaft 20 in a clockwise direction will cause the contact arm of the rheostat to be moved until the element 39 strikes against the tripping pin 29 at some intermediate point on the quadrant. As the shaft moves, the pin will cause the element 39 to be turned on its axis and thus cause the projection 36' to ride up on its cam surface toward projection 38 and thus automatically disengage the rod 33 from the collar 31 as soon as the projection 36' rides upwardly on the inclined cam

surface to a point sufficient to withdraw the rod from the slot 31'. Continued movement of the shaft 20 then has no further effect upon the particular rheostat considered and leaves the contact arm of that rheostat in an intermediate position, with the rod 33 pressing against the outer surface of the collar 31 by force of the spring 34. This position may give a half dimming of the lights, or dimming to any desired extent, depending upon the position of the tripping pin 29 on the quadrant. When the shaft 20 is afterwards turned in a counter clockwise direction, the rod 33 will be forced into the slot 31' by pressure of the spring 34 as soon as the slot comes opposite the end of the rod, the projection 36' sliding down on the inclined cam surface and turning the rod 33 back to its former position. The shaft 20 will then be coupled to the rheostat handle and operate the rheostat by movement of the handle in the counter clockwise direction. Obviously any desired number of the rheostats can be controlled so as to be unlocked by their respective tripping means at corresponding points of adjustment, or at any desired intermediate point, depending upon the positions to which their respective tripping pins 29 are adjusted, and will again be coupled to the shaft upon the reverse movement thereof at the same points at which they were uncoupled.

Similarly, if desired, the unlocking can be accomplished during the movement of shaft 20 in the reversed direction so that some of the lighting circuits will be controlled to cause their lights to remain dimmed while others are being brightened by continued movement of the shaft 20. Obviously the handles 35 may be turned to adjust the position of the elements 39 and the pins 29 may be adjusted to their desired positions so as to secure any predetermined character of operation during the movement of the drive shaft, and these preliminary adjustments may be made at convenient times between the operation of the drive shaft.

Although I have described one embodiment of my invention it will be understood that other modifications may be made without departing from the scope thereof.

I claim:

1. The combination of a plurality of electric circuit controlling devices, a driving element therefor, and individual coupling means between said devices and said element whereby said devices may be simultaneously operated by movement of said element and certain of said devices automatically disconnected from said element, and adjustable means for causing said disconnection to occur at any desired points in the movement of said element.

2. The combination of an electric circuit controlling device, a driving element there-

for, coupling means between said device and element, and automatic means for uncoupling during the movement of said element, and adjustable means for automatically uncoupling at any desired point during the movement of said element.

3. The combination of an electric circuit controlling device, a driving element therefor, coupling means between said device and element, adjustable means for automatically uncoupling at any desired point during the movement of said element and a manual element whereby said device may be operated independently of said driving element.

4. The combination of an electric circuit controlling device, a driving element therefor, a member movable on said element connected to said device, coupling means between said element and said member, and adjustable tripping means for releasing said coupling means at any desired point during the movement of said element.

5. The combination of an electric circuit controlling device, a driving element therefor, a member movable on said element connected to said device, coupling means between said element and said member, an adjustable tripping element, and means carried by said member adapted to be engaged by said tripping element for releasing said coupling means.

6. The combination of an electric circuit controlling device, a driving element therefor, a member movable on said element connected to said device, coupling means between said element and said member, an adjustable tripping element, and means carried by said member adapted to be engaged by said tripping element for releasing said coupling means, and a handle adapted to control said coupling means and to move said member.

7. The combination of an electric circuit controlling device, a driving element therefor, a member movable on said element connected to said device, coupling means between said element and said member, a stationary frame, a tripping element adjustable to various positions on said frame, and means carried by said member adapted to be engaged by said tripping element for releasing said coupling means.

8. The combination of an electric circuit controlling device, a driving element therefor, a member movable on said element connected to said device, coupling means between said element and said member, a stationary quadrant having a series of holes, a tripping element adapted to be adjusted to engage said holes, and means carried by said member adapted to be engaged by said tripping element for releasing said coupling means.

9. The combination of an electric circuit

controlling device, a drive shaft therefor, a member pivoted on said shaft connected to said device, a plunger carried by said member biased to couple said member to said shaft, a handle on said plunger, said member and said plunger having inter-related surfaces for causing said plunger to uncouple said member from said shaft when said plunger is turned on its axis, a tripping element, and an element carried by said plunger and adapted to engage said tripping element.

10. The combination of a plurality of electric circuit controlling devices, a driving element therefor, and individual coupling means between said devices and said element whereby said devices may be simultaneously operated by movement of said element and certain of said devices automatically disconnected from said element during its movement in one direction and automatically reconnected with said element during its movement in the opposite direction.

11. The combination of a plurality of electric circuit controlling devices, a driving element therefor, and individual coupling means between said devices and said element whereby said devices may be simultaneously operated by movement of said element and certain of said devices automat-

ically disconnected from said element at any desired points and automatically reconnected with said element at corresponding points when said element is moved in the opposite direction. 35

12. The combination of an electric circuit controlling device, a driving element therefor, coupling means between said device and said element, and adjustable means for automatically uncoupling at any desired point during the movement of said element in one direction and for recoupling at said point during movement of said element in the reverse direction. 40

13. The combination of an electric circuit controlling device, a driving shaft therefor, a member pivoted on said shaft connected to said device, a plunger carried by said member biased to couple said member to said shaft, said member and said plunger having inter-related cam surfaces for causing said plunger to uncouple said member from said shaft when said plunger is turned on its axis, a tripping element adapted to be engaged by said plunger to turn said plunger until said cam surfaces have such relationship as to cause the plunger to uncouple said member from said shaft, and means whereby said tripping element may be adjusted to different positions. 50 55 60

ALFRED E. WALLER.
